UNITED STATES PATENT OFFICE

NORMAN V. KREGER, OF BEN AVON, PENNSYLVANIA

REAR-CURTAIN-OPERATING DEVICE

Application filed May 9, 1939. Serial No. 361,748.

This invention relates to an automotive accessory in the form of a structure to be interposed between a rear window curtain, and the intake manifold, for automatically raising and lowering the curtain as conditions require to promote safe driving, particularly at night.

It is a well established fact that when headlights from a machine in the rear are projected through the rear window and against the windshield and rear view mirror, uncontrollable reflections are produced, which interfere with safe driving. It is therefore advantageous under certain conditions to lower the rear curtain to avoid this nuisance.

I am aware of the fact that devices have been provided for accomplishing this result, without requiring the operator reaching over the front seat and lowering the curtain manually. In other words, I am aware of the fact that so-called automatic devices have been patented for accomplishing this result. The present invention relates to an improved means for accomplishing the result by way of a valved suction line, connected with the intake manifold at one end and with a piston device at the opposite end, the cylinder piston device having an operating connection 30 with the spring wound rear curtain.

In carrying out the invention I have evolved and produced a novel structural arrangement which is characterized by an unusually simplified organization of parts 35 which are intimately associated for accomplishing the desired result in an efficient manner. The particular details and their specific association and arrangement will become more readily apparent from the following 40 description and drawings.

In the drawings:

Figure 1 is a diagrammatic elevational view showing the complete suction system and operating means for the rear curtain as 45 constructed in accordance with the present invention.

Figure 2 is a fragmentary detail view, in section and elevation, showing the suction line connected with the intake manifold.

50 Figure 3 is a vertical sectional view

through the piston and cylinder construction which is associated directly with the rear curtain.

Figure 4 is a detail section and elevation of the manually manipulated control valve 55 arranged on the instrument board within convenient reach of the driver.

Figure 5 is a fragmentary detail elevational view of the revised curtain.

Figure 6 is an end view of Figure 5, looking in the direction from left to right.

Referring first to Figure 1, wherein the complete arrangement is seen, it will be observed that the reference character 7 designates the body of the vehicle and 8 designates 65 the rear window. The reference character 9 designates generally the rear curtain. The motor is designated by the reference character 10 and the instrument board by the reference character 11. The reference character 12 designates the intake manifold, with which this appliance is associated. In accordance with the present invention, a manually manipulated control valve, generally designated at 13 is mounted on the instrument board. This particular detail is seen 70 particularly in Figure 4. Reference being had to this figure, it will be observed that it comprises a cylinder or casing 14, equipped with an elbow 15. The projecting end portion of the elbow provides a nipple connection 75 for the rubber tube 16, which leads to and is operatively connected with the intake manifold.

The inner end portion of this elbow is 80 flared as designated at 17 to provide a conical valve seat and the pointed end of the needle valve 18 is adapted to seat thereon. The needle valve 18 is threaded through the end 85 of the cylinder or casing 13 which is opposed to the seat 17 and its outer end is provided with suitable means to be gripped by the operator for screwing said valve toward or away from said seat.

On the bottom of the casing is a nipple 19, 90 with which the suction delivery pipe 19' is connected.

Referring now to Figure 2, it will be seen that 20 designates a cap plug or fitting carrying a tube connection 21, with which the 100

hose 16 is connected. This hose, as above stated, is in turn connected with the projecting end portion of the elbow 15, thereby rendering the suction subject to the action of the valve 18.

5 The pipe 19' extends rearwardly in any suitable manner, where it is connected with the curtain actuating means. This is seen better in Figure 3. It comprises a vertical cylinder 22, in which a piston 23 is mounted for sliding movement. Connected with this piston is a cord or similar flexible element 24 which is in turn operatively connected with the flexible portion of the rear curtain 9. Incidentally it is necessary to revise the curtain structure slightly. For instance, the spring drum of this curtain is ordinarily provided with a pawl 25 (see Figure 6) which is engageable with a ratchet tooth on the head 26. In accordance with the present invention, this tooth is eliminated by substituting a lead filler 27, thereby rendering the pawl and ratchet means ineffective.

10 The spring means, however, is still effective, and serves to return the curtain to rolled condition. Thus, it is obvious that the suction control device serves to pull the curtain down and the spring serves to return it. The suction is brought into play when 15 the valve 18 is opened, and is released when the valve is closed. Obviously then, when it is desired to lower the curtain, the valve is simply opened, thereby permitting suction to pass through the tubes or pipes 16 or 19' 20 and to act upon the piston in the cylinder 22. This in turn acts upon the cord and pulls the curtain down. When, however, the suction is released, the spring returns the curtain to raised position.

25 40 It is thought that by considering the description in connection with the drawings, a clear understanding of the construction, features and operation of the invention will be had. Therefore a more lengthly description 45 is regarded as unnecessary.

50 Minor changes in shape, size and rearrangement of details may be resorted to in actual practice so long as no departure is made from the adjoining claims.

55 I claim:

1. In a suction operated device for actuating automobile curtains comprising a control valve including an elongated casing, a tubular elbow, an arm on the elbow projecting through the side wall of the casing, the other arm of the elbow disposed longitudinally in the casing, a valve seat on the free end of the longitudinal arm, and a manually operable valve threaded through one end wall 60 of the cylinder and engageable with the valve seat.

65 2. In a suction operated device for actuating automobile curtains comprising a control valve including a cylindrical casing, a tubular elbow, one arm of the elbow pro-

jecting through an intermediate portion of the side wall of the casing in a manner to mount the elbow on the casing, the other arm of the elbow disposed longitudinally and centrally in the casing and having a flared free end portion constituting a valve seat disposed in spaced opposed relation to one of the end walls of the casing, a manually operable valve threaded through said one end wall and engageable on the seat, a nipple projecting from the casing for connecting a suction pipe to said casing, the projecting end portion of the first named arm of the elbow constituting coupling means for another suction pipe.

70 75 80 In testimony whereof I affix my signature.
NORMAN V. KREGER.
